UNITED STATES PATENT OFFICE.

WILLIAM A. KNOOP, OF EAST NORTHPORt, NEW YORK, ASSIGNOR TO WESTERN ELECTRIC COMPANY, INCORPORATED, OF NEW YORK, N. Y., A CORPORATION OF NEW YORK.

REGULATING SYSTEM.

Application filed July 31, 1922. Serial No. 578,568.

To all whom it may concern:

Be it known that I, WILLIAM A. KNOOP, a citizen of the United States, residing at East Northport, in the county of Nassau, State of New York, have invented certain new and useful Improvements in Regulating Systems, of which the following is a full, clear, concise, and exact description.

This invention relates to regulating systems, and particularly to a voltage regulating system employing an electric discharge device.

An object of this invention is to supply a constant voltage to a load circuit independent of variations in the voltage of the supply source.

Another object is to provide an electric discharge regulator for regulating an electrical characteristic of a source of voltage or current.

Another object is to obtain a substantially constant voltage across the anode and cathode electrodes of an electric discharge repeater.

In accordance with one form of this invention these objects are accomplished by employing a three electrode vacuum tube comprising an anode, a cathode and a control electrode which operates so that a variation in the potential impressed upon the control electrode will vary to a much greater extent the space current flowing between the anode and cathode electrodes. The anode and cathode are connected across the line upon which it is desired to impress constant voltage.

The potential of the control electrode is made responsive to variations in the source of voltage supply in such a manner that an undesired increase, for example, in voltage, increases the space current between the anode and cathode. By providing a resistor of suitable magnitude in series with the source of voltage and the anode and cathode, the resulting increase in space current will produce an increase in the IR drop in the resistance to compensate for the increase in voltage and to hold substantially constant the potential difference between the anode and cathode. The load circuit may, therefore, be connected across the anode and cathode electrodes and consequently will be supplied with a constant voltage regardless of the variations in the potential of the source.

Referring to the drawings:

Fig. 1 illustrates this invention embodied as a voltage regulator for supplying a constant voltage to a load circuit.

Fig. 2 shows how the system of Fig. 1 may be modified to adapt the regulator to variations in the load circuit to which it is connected.

Fig. 3 illustrates a form of this invention that does not require a constant source of potential for the control electrode of the regulator.

Fig. 1 illustrates, in the block designated 5, a load circuit to which it is desired to supply constant voltage from a battery or other source of potential 6. In accordance with this invention the leads 7 and 8 going to the load circuit are connected by a shunt path comprising the anode 9 and cathode 10 of a three-electrode discharge device or amplifier 11. Connected also across leads 7 and 8 is a high resistance 12, an intermediate point of which preferably through a constant source of voltage 13 is connected to the control electrode 14 of the vacuum tube regulator. Resistance element 15, shown in series with the source of voltage 6 and the anode 9 and cathode 10, is of a definite value predetermined in a manner hereinafter described.

The manner in which voltage regulation takes place may now be explained as follows:

If, for example, voltage of source 6 should suddenly increase over its normal value, the potential drop in resistance 12 will increase thereby making less negative, or more positive as the case may be, the potential of control electrode 14 with respect to cathode 10. This increase in the voltage of control electrode 14 will produce a much greater increase in the space current flowing between the anode 9 and the cathode 10. The increase in space current in tube 11 will cause an increase in the current flowing through resistance 15, and resistance 15 should, therefore, have such a value that the resulting increase in the IR drop across the terminals of the resistance just compensates for the increase in the voltage of source 6. With such an adjustment, the voltage across the anode 9 and cathode 10 of the vacuum tube will remain constant and, consequently, the voltage supplied to

the load circuit 5 will remain constant regardless of the changes in the source of voltage 6. The operation of the regulator for a decrease in voltage of source 6 may 5 be explained in a similar manner, since such a decrease would make the control electrode 14 more negative thereby decreasing to a much greater extent the space current in tube 11 and the current flowing in resistance 15 such that the decrease in the IR drop in resistance 15 is sufficient to compensate for the decrease in voltage of source 6.

This arrangement therefore supplies a constant voltage to the load circuit and will 15 also supply a constant current thereto providing the impedance of the load is constant, and this invention is preferably used with a constant load impedance.

This regulation may be explained mathematically as follows: E_c , the potential of the grid battery 13, should preferably have a potential equal to or slightly greater and opposite

$$25 \quad \frac{E_B r_1}{r_1 + r_2}$$

where E_B is the potential of source 6; r_1 that portion of resistance 12 included between the control electrode and the cathode; 30 r_2 that portion of resistance 12 included between the anode and control electrode; and r_3 , resistance 15. This will result in making the total potential of the grid with respect to the filament zero or slightly negative. Under these conditions no current will be drawn from the grid potential battery.

Assume that the device is operating and that the potential E_B should rise by an amount ΔE_B . The potential of the grid 40 will rise an amount

$$\frac{\Delta E_B r_1}{r_1 + r_2}$$

45 Assume that the tube is working on practically the straight line part of its grid voltage-space current characteristic having a slope

$$50 \quad \frac{dI_p}{dE_g}$$

where I_p represents the space current and E_g the grid voltage. A change in E_g of

$$55 \quad \frac{\Delta E_B r_1}{r_1 + r_2}$$

will cause an increase in I_p of

$$60 \quad \frac{\Delta E_B r_1}{r_1 + r_2} \times \frac{dI_p}{dE_g}$$

This increase of I_p flows through r_3 causing an increased RI drop equal to

$$65 \quad \frac{E_B r_1}{r_1 + r_2} \times \frac{dI_p}{dE_g} \times r_3$$

This, in order that E_p remain constant, must equal ΔE_B or

$$\frac{\Delta E_B r_1}{r_1 + r_2} \times \frac{dI_p}{dE_g} \times r_3 = \Delta E_B$$

70 or solving for r_3 ,

$$75 \quad r_3 = \frac{r_1 + r_2}{r_1} \times \frac{1}{\frac{dI_p}{dE_g}}$$

The last expression designates the value of the resistance 15 of Fig. 1 in terms of the value of resistance 12 and the slope of the grid voltage-space current characteristic of the vacuum tube 11.

The arrangement of Fig. 2 is similar to that of Fig. 1 in that resistance 20, that part of resistance 21 between resistance 20 and adjustable contact 22, and resistance 23 correspond to resistance 15 of Fig. 1. Resistance 21, however, acts as a potentiometer since by adjustment of movable contact 22 any desired constant fraction of the voltage of source 24 may be impressed upon the load circuit. An additional resistance 26 is provided in Fig. 2 in the shunt circuit including the anode 27 and cathode 28 of the vacuum tube regulator 29, which resistance should have a value at least as great as the effective resistance between the anode 27 and cathode 28 and may sometimes have a value several times greater. The purpose of resistance 26 is to make the grid voltage space current characteristic of the vacuum tube approximate a straight line over a wider voltage range than may be obtained with the resistance omitted.

The operation of the arrangement of Fig. 2 is similar to that of Fig. 1 in that a variation in the voltage of the generator or other source 24 will change the potential drop in resistance 30 thereby changing the potential of grid 31 and the space current between the anode and cathode in such a manner that the resulting change in the IR drop in resistance 20, 21 and 23 compensates for the variation in the source 24.

In the form shown in Fig. 3 a battery or other source of constant voltage for maintaining the control electrode at a negative potential is unnecessary. In this figure the potential of the grid 35 is always positive to the cathode 36 so that a certain amount of grid current is present in the tube. The grid and cathode are connected across the output leads of generator 37 in series with a resistance 38, while the anode 39 and cathode are connected in series with a second resistance 40 and the generator. The values of the resistances should be so chosen that an increase, for example, in the voltage of source 37 will make the grid more positive thereby increasing the space current of tube 41 and increasing the IR drop in resistance 40 an amount sufficient to compen-

sate for the increase in source 37. The arrangement of this figure has the advantage that both the grid voltage-anode current characteristic and grid voltage-grid current characteristic curves of the tube depart from a straight line in substantially the same manner, so that the curvature of one is compensated for at least in part by the other.

10 The preferable values for the arrangement of Fig. 3 may be obtained as follows: Let E_g and I_g be the grid voltage and grid current, E_B the voltage of the generator, E_p and I_p the anode voltage and anode current, r_g the resistance 38, and r_1 the resistance 40.

If a change ΔE_B takes place in the generator voltage,

$$\begin{aligned} 20 \quad \Delta E_g &= \Delta E_B - \Delta I_g r_g \\ &= \Delta E_B - r_g \Delta E_B \frac{dI_g}{dE_B} \\ 25 \quad \Delta E_B &= \Delta E_g \left(1 + r_g \frac{dI_g}{dE_g} \right) \\ &= \Delta I_g r_1 \\ 30 \quad \Delta E_g \left(1 + r_g \frac{dI_g}{dE_g} \right) &= \Delta E_g \frac{dI_p}{dE_g} r_1 \\ &= \frac{dI_p}{dE_g} r_1 = 1 + r_g \frac{dI_g}{dE_g} \\ 35 \quad r_1 &= \frac{1}{\frac{dI_p}{dE_g}} + r_g \frac{dI_g}{dE_g} \end{aligned}$$

The last equation gives the value of resistance 40 in terms of resistance 38 and the slopes of the curves of the tube.

40 A satisfactory arrangement for setting the regulator when the variations to be eliminated are audible is to connect in series a telephone receiver and a large capacity in place of the load. E_B is then applied and 45 E_p set to the desired value by means of varying value of resistance 15. The movable contact on resistance 12 may then be varied until a minimum noise is heard in the receiver.

50 It is to be understood that this invention is not limited to the specific embodiments above described, but as will occur to those skilled in the art, the above arrangements may be substantially modified without departing in any way from the spirit of this invention as defined in the appended claims.

What is claimed is:

1. In combination, a source of voltage subject to variations, a load circuit, and means for supplying said load circuit with a constant voltage, said means comprising an electric discharge device having an anode, a cathode and a control electrode, said load circuit being connected across said anode and cathode, means responsive to variations

in a characteristic of said source for producing variations in the potential of said control electrode and a resistance connected in series with said source, said anode and said cathode.

2. In combination, a load circuit, a source of voltage, connections for supplying said load circuit with constant voltage from said source, a vacuum tube having an anode, a cathode and a control electrode, said anode and cathode being connected in shunt to said connections, an impedance connected across said connections, a connection from an intermediate point of said impedance to said control electrode, and an impedance in series with said first connections and located electrically between said source and said tube.

3. In combination, a vacuum tube having an anode, a cathode and a control electrode, a resistance, a series circuit connection comprising said source, said resistance, said anode and said cathode, and means responsive to changes of voltage of the said source to change the potential of said control electrode for holding substantially constant the voltage across said anode and said cathode.

4. In combination, a vacuum tube having an anode, a cathode and a control electrode, a source of voltage, and impedance, a series circuit connection comprising said source, said anode, said cathode and said impedance, a second impedance in shunt to said source, and a connection for including a portion of said second impedance between said control electrode and said cathode to cause said control electrode to be responsive solely to variations of said source.

5. In combination, a vacuum tube having an anode, a cathode and a control electrode, a source of voltage for supplying space current to said tube, means for holding substantially constant the voltage drop across said anode and cathode, said means comprising a resistance in series with said source, said anode and said cathode, a second resistance in shunt to said source, and a connection from said second resistance to said control electrode.

6. In combination, a vacuum tube having an anode, a cathode and a control electrode, a source of voltage for supplying space current to said tube, means responsive to a voltage increase by said source for varying the potential of said control electrode, and means responsive to the increase of space current of said tube for causing a fall of potential between said source and said tube equal to the increase of voltage of said source, whereby a substantially constant voltage is maintained across said anode and said cathode.

7. In combination, a vacuum tube having an anode, a cathode and a control electrode, a source of voltage, and means for maintaining a substantially constant voltage across

said anode and cathode, said means comprising a resistance in series with said source, said anode and said cathode, a second resistance in shunt to said source, a 5 connection from said resistance to said control electrode such that a portion of said second resistance and said first resistance is included in circuit between said control electrode in circuit between said control electrode 10 of said second resistance being included in circuit between said control electrode and said cathode, means for supplying a constant negative potential to said control electrode, said first resistance having a value 15 determined by the slope of the control electrode voltage space current characteristic of said vacuum tube.

8. In combination, a vacuum tube having an anode, a cathode and a control electrode, 20 a source of voltage, means for maintaining a substantially constant voltage across said anode and cathode, said means comprising a resistance in series with said source, said anode and said cathode, a second resistance 25 in shunt to said source, a connection from said resistance to said control electrode such

that a portion of said second resistance and said first resistance is included in circuit between said control electrode and said anode, said first named resistance having a 30 value approximately equal to the value of said second resistance divided by the product of said second named portion of said resistance and the slope of the control electrode voltage-space current characteristic of 35 said tube at the point of operation.

9. In combination, a direct current source of voltage subject to variations, a load circuit, and means for supplying constant current to said load circuit, said means comprising a vacuum tube having an anode, a cathode and a control electrode, said load circuit being connected across said anode and cathode, means responsive to variations in a characteristic of said source for producing variations in the potential of said control electrode, and a resistance connected in series with said source, said anode and said cathode. 40 45

In witness whereof, I hereunto subscribe my name this 29th day of July A. D., 1922. 50
WILLIAM A. KNOOP.
